UNITED STATES PATENT OFFICE.

ALBERT P. STEBLER, OF NIAGARA FALLS, NEW YORK.

CAN OPENER.

1,405,170.

Specification of Letters Patent. Patented Jan. 31, 1922.

Application filed November 5, 1920. Serial No. 421,812.

To all whom it may concern:

Be it known that I, ALBERT P. STEBLER, a citizen of the United States, residing in Niagara Falls, in the county of Niagara and State of New York, have invented new and useful Improvements in Can Openers, of which the following is a specification.

This invention relates to a can opener and has for its object the production of a can opener which can be readily advanced after each cutting stroke, which is not liable to slip out of the slit in the can during the cutting operation, which reliably holds down the severed part of the can so as to permit of making a clean cut in the can close to the body of the same, which is not liable to slip on the can and injure the hand of the operator, and which is simple in construction, efficient in operation and capable of being manufactured at low cost.

In the accompanying drawings: Figure 1 is a perspective view of my improved can opener showing the same in position ready to begin a cutting stroke on the lid of the can. Figure 2 is a vertical longitudinal section of the same taken in a plane parallel with the direction of the cutting movement and on line 2—2, Fig. 3. Figure 3 is a sectional view taken on line 3—3, Fig. 2. Figure 4 is a fragmentary longitudinal section taken on line 4—4, Fig. 5 and viewing the cutting blade from the side opposite to that shown in Figs. 1 and 2. Figure 5 is a vertical transverse section taken on line 5—5, Fig. 4. Figure 6 is a detached perspective view of the shank and blade. Figure 7 is a similar view of the bearing device forming part of the can opener. Figure 8 is a similar view of the blank from which the bearing device is constructed. Figure 9 is a fragmentary sectional elevation of a can showing its lid cut out in a manner contemplated by my improved can opener.

Similar characters of reference refer to like parts throughout the several views.

Although this can opener may be used for opening tin cans of various forms the same is more particularly designed for cutting out a circular lid 10 from the head of a can close to the inner side of the cylindrical wall or body 11 thereof leaving the seam 12 which connects the head with the body attached to the latter, as shown in Fig. 9, thus avoiding a ragged edge on the opened can and per-

mitting of using the same as a cup or receptacle in the kitchen or elsewhere.

In its general organization my improved can opener comprises a longitudinal shank provided with a cutting blade, a bearing device for supporting the tool on the can, and a handle for operating the tool.

The shank 13 is preferably constructed of a strip or bar of metal such as iron or steel, which is flat and provided with upper and lower longitudinal edges. The cutting blade 14 is curved and projects forwardly and downwardly from the front end of the shank and is formed integrally therewith. The cutting edge 15 is formed on the periphery thereof and extends from the pointed front end 16 thereof to its rear end adjacent to the junction of the same with the shank. The pointed front end of the blade is arranged below a line co-incident with the lower longitudinal edge of the shank, as shown in Figs. 1, 2, 4 and 6, whereby upon turning the blade upwardly by the depression of the shank and the handle connected therewith, the blade will still remain within the slit or kerf which has been cut in the can head when the blade has completed its stroke and the shank or handle rest on top of the can, thus avoiding disengagement of the blade from the can after each cutting stroke but instead keeping the blade within the kerf 17 and enabling the cutting of the lid to be progressed very rapidly and effectively.

The rear part of the blade adjacent to the shank, as best shown in Fig. 3, is constructed to form a neck 18 which is produced by reducing the thickness of the rear part of the blade in a direction at right angles to the cutting movement of the blade. By this means the blade after each cutting operation can be advanced and pushed fully with the thin rear part of its cutting edge into engagement with the front end of the kerf and enable the blade to immediately begin its cutting action upon turning the same upwardly and thus facilitate the work of removing the lid or opening the can.

Supporting means are provided to properly support the can opener on the top of the can while the same is in operation and also to prevent the can opener from slipping backwards and preventing the lid which is being cut out from interfering with making a clean cut, especially when this cut is to be

made next to the inner side of the body or wall of the can. In their preferred form the supporting means comprise two curved bearing shoes 19, 20 arranged respectively 5 on the outer and inner sides of the shank adjacent to the rear end of the blade and having their peripheries co-axial and facing downwardly and forwardly. The outer shoe is preferably provided on its curved periphery with knurling so as to enable the same to obtain a good grip on the seamed marginal part of the can and prevent the tool from slipping backwards. This knurling, as 10 shown at 21 in Figs. 1, 2 and 7, preferably 15 has the form of transverse ribs which are V-shaped in cross section and thus effectively prevent the tool from slipping either forward or backward on the can during the cutting operation. The inner bearing shoe 20 20 serves to hold down the severed portion of the lid, which tends to rise, and thus keeps the same down so that the blade can make an effective cut which is clean and close to the inner side of the wall around the entire 25 circumference of the can, thereby avoiding the rough or ragged edge on the can after the lid is cut from the same which not only renders it safer to handle the can when removing its contents but also enabling the 30 can to be used as a cup or as a receptacle.

The two shoes of the bearing or supporting device are preferably connected at their rear ends by a short transverse neck 22, as shown in Figs. 7 and 8. One of these shoes, 35 preferably the outer one is provided with a rearwardly projecting heel 23, and on its inner longitudinal edge this heel is provided with an upstanding longitudinal attaching flange 24 which is secured to the inner side 40 of the tool shank, thus supporting the bearing means thereon. In the preferred construction the two bearing shoes, the neck between the same, the heel and the attaching flange are formed integrally from a single 45 blank of sheet metal, as shown in Fig. 8, thereby simplifying the construction and reducing the cost of manufacture.

In order to make the underside of the shank and the bearing device flush, the lower 50 longitudinal edge of the shank is provided with a notch 25 which receives the neck and heel of the supporting device, as shown in Figs. 2 and 4, thus avoiding any objectionable corners on the tool which might injure 55 the hand and also permit the same to be cleaned and kept more easily in a sanitary condition.

The handle of the tool is preferably made 60 hollow and constructed of two sections 26, 27 and are divided lengthwise and receive 65 between them the rear part of the shank of the tool. The front end 28 of the handle section bears only against the shank but the front part of the other handle section not only bears against the shank but is also

provided with a laterally projecting off-set pocket 29 forming a pocket which receives the rear end of the attaching flange of the supporting means.

Any suitable means may be employed for 70 holding the several parts of the tool in assembled position, for instance, as shown in Figs. 1, 2, 3 and 4, this may be accomplished by two rivets 30 passing transversely through the front parts of the handle sections and 75 the shank and flange lying between the same, and a rivet 31 passing through the rear parts of the handle sections and the shank.

This tool is not only very efficient for cutting out lids of tin cans but the same is also 80 very strong and durable and not liable to get out of order.

I claim as my invention:

1. A can opener comprising a longitudinal shank, and a curved vertically swinging 85 blade which extends forwardly and downwardly from said shank and its cutting edge on the periphery thereof and has that part thereof adjacent to said shank constructed to form a neck which is reduced in thickness 90 in a direction at right angles to the cutting movement of the blade, so that the front part of the blade is thick and the rear part of the same is narrow, said front thick and rear narrow parts being alternately engaged 95 with the part to be cut when the can opener is used.

2. A can opener comprising a longitudinal shank, a curved blade which extends forwardly and downwardly from said shank 100 and has its cutting edge on the periphery thereof, and means for supporting the shank and blade on a can including two curved bearing shoes arranged on opposite sides of the shank and having their peripheries co-axial and facing forwardly and downwardly, and a neck connecting the rear parts of said shoes.

3. A can opener comprising a longitudinal shank, a curved blade which extends forwardly and downwardly from said shank and has its cutting edge on the periphery thereof, and means for supporting the shank and blade on a can including two curved bearing shoes arranged on opposite sides of the shank and having their peripheries co-axial and facing forwardly and downwardly, and a neck connecting the rear parts of said shoes, and said shank being provided on its underside with a notch which receives said neck.

4. A can opener comprising a longitudinal shank, a curved blade which extends forwardly and downwardly from said shank and has its cutting edge on the periphery 125 thereof, and means for supporting the shank and blade on a can including two curved bearing shoes arranged on opposite sides of the shank and having their peripheries co-axial and facing forwardly and downwardly, 130

a neck connecting the rear parts of said shoes, a heel extending rearwardly from one of said shoes, and a flange arranged at one of the longitudinal edges of said heel and secured to one side of said shank.

5. A can opener comprising a longitudinal shank, a curved blade which extends forwardly and downwardly from said shank and has its cutting edge on the periphery thereof, and means for supporting the shank and blade on a can including two curved bearing shoes arranged on opposite sides of the shank and having their peripheries co-axial and facing forwardly and downwardly, 10 a neck connecting the rear parts of said shoes, a heel extending rearwardly from one of said shoes, and a flange arranged at one of the longitudinal edges of said heel and secured to one side of said shank, said shank 15 being provided on its lower longitudinal edge with a notch which receives said neck and heel.

6. A can opener comprising a longitudinal shank, a curved blade which extends forwardly and downwardly from said shank 25 and has its cutting edge on the periphery thereof, and means for supporting the shank and blade on a can including two curved bearing shoes arranged on opposite sides of the shank and having their peripheries co- 30 axial and facing forwardly and downwardly, a neck connecting the rear parts of said shoes, a heel extending rearwardly from one of the longitudinal edges of said heel and secured 35 to one side of said shank, and a longitudinally divided handle having its sections secured to opposite sides of said shank and flange, and one of said handle sections being provided at its front end with a laterally 40 offset pocket which receives the rear part of said flange.

ALBERT P. STEBLER.
